DEMOUNTABLE TRACTION BOOSTER FOR MOTOR VEHICLE TIRES

Leonard Leslie Lewis, 35 Carroll St.,
Poughkeepsie, N.Y. 12601

Filed July 22, 1974, Ser. No. 490,504

Term of patent 7 years

Int. Cl. D12—16

U.S. Cl. D12—154

FIG. 2

FIG. 1

FIG. 1 is a perspective view of a demountable traction booster for motor vehicle tires showing my new design; and

FIG. 2 is an enlarged fragmentary side elevational view thereof taken along line 2—2 in FIG. 1 showing the adjustable length latch.

I claim:

The ornamental design for a demountable traction booster for motor vehicle tires, as shown.
